UNITED STATES PATENT OFFICE.

CHRISTOPHER C. BRADLEY, OF SYRACUSE, NEW YORK.

THILL-COUPING.

SPECIFICATION forming part of Letters Patent No. 747,041, dated December 15, 1903.

Application filed August 1, 1903. Serial No. 167,868. (No model.)

To all whom it may concern:

Be it known that I, CHRISTOPHER C. BRADLEY, of Syracuse, in the county of Onondaga, in the State of New York, have invented new and useful Improvements in Thill-Couplings, of which the following, taken in connection with the accompanying drawings, is a full, clear, and exact description.

This invention relates to improvements in thill-couplings in which the coupling-pin is provided with an annular groove in which is seated a suitable packing of leather or similar material, the object being to provide a narrow antirattling-bushing upon the coupling-pin which is engaged by the jaws of the draft-eye, whereby the draft-eye and thill-coupling are free to rock upon each other, both circumferentially and laterally.

In the drawings, Figure 1 is a side elevation of a thill-coupling embodying the features of my invention. Figs. 2 and 3 are perspective views of the thill-iron and coupling-pin, showing the packing in operative position in Fig. 2 and removed in Fig. 3. Fig. 4 is a transverse sectional view taken on line 4-4, Fig. 1, showing the coupling-pin in elevation. Figs. 5 and 6 are perspective views, respectively, of the detached packing-ring and its retaining-spring.

Similar reference characters indicate corresponding parts in all the views.

In Fig. 1 of the drawings I have shown a thill-coupling consisting of a draft-eye 1, a coupling-pin 2, and a packing 3. The draft-eye preferably consists of a fixed jaw 4 and a movable jaw 5, hinged at 6 to the front end of the fixed jaw. A link 7 is detachably engaged with the free end of the jaw 5 for holding it in its operative position, the lower end of said link being pivotally connected to a lever 8, which latter is fulcrumed at 9 to the free end of a spring 10, said spring, together with the fixed jaw 4, being secured in any well-known manner to an axle 11.

The jaws 4 and 5 are provided with inner or adjacent concave substantially spherical bearing-faces 12, which engage the periphery of the packing-ring when the jaws are in operative position.

The coupling-pin 2 is provided with an enlarged spherical knuckle 13, having a substantially central annular groove 14 for receiving

the packing 3. This packing preferably consists of a narrow annular ring of leather or similar material, split longitudinally through one of its sides and placed in the groove 14 of the knuckle 13, said ring being of substantially the same width as the groove and abuts against the side walls of said groove, which prevents its lateral displacement; but the thickness of the ring is slightly greater than the depth of the groove, so as to project radially beyond the spherical surface of the knuckle 13. The object of this is to provide a narrow bearing for the jaws and to hold said jaws out of contact with the metal coupling-pin, so that said coupling-pin and jaws are free to rock upon each other circumferentially or transversely without liability of bringing the metallic parts into contact, and by making the packing-ring narrow it is evident that the friction incidental to the rocking movement of one of the parts upon the other is reduced to a minimum and still the device retains all the strength of the coupling-pin and jaws.

A retaining member consisting of a split spring-ring 15 is sprung open and placed upon the periphery of the packing to hold it in its seat in the groove 14 and to prevent as far as possible the distortion of the packing while the coupling is in use.

In assembling the parts of the coupling the split packing-ring 3 is sprung open and placed upon the spherical knuckle 13 in the groove 14, and the spring-retainer 15 is then similarly placed upon the periphery of the packing-ring, after which the coupling-pin, with the packing thereon, is placed between the open jaws, and the jaws are then closed and locked by means of the link 7 and lever 8.

Having thus described my invention, what I claim, and desire to secure by Letters Patent, is—

1. In a thill-coupling the combination with a draft-eye, of a coupling-pin having an annular groove and a packing inserted in the groove and projecting slightly beyond the periphery of the pin.

2. In a thill-coupling, a draft-eye and a coupling-pin, one of the parts having an annular groove in combination with a packing-ring inserted in and of greater thickness than the depth of the groove for holding the contiguous

ous faces of the draft-eye and coupling-pin out of contact.

3. A thill-coupling comprising a draft-eye having spherical bearing-faces, a coupling-pin having a spherical knuckle formed with an annular groove and a packing-ring arranged in the groove.

4. A thill-coupling comprising a draft-eye, a coupling-pin having a spherical knuckle formed with an annular groove and a split

packing-ring arranged in the groove and projecting slightly beyond the periphery of the knuckle.

In witness whereof I have hereunto set my hand this 29th day of July, 1903.

CHRISTOPHER C. BRADLEY.
